FOUNTAIN PEN

Joseph L. Hoyle, Hartford, Conn.

Application May 31, 1934, Serial No. 728,445

1 Claim. (CL 120—42)

This invention relates to improvements in writing devices and pertains particularly to an improved writing pen of the type commonly known as a fountain pen.

5 The primary object of the present invention is to provide a fountain pen of a double type whereby inks of two different colors may be carried in the barrel and either color made use of without having to make any adjustment of any 10 parts of the pen, the conversion being obtained simply by turning the pen barrel through a half rotation in the hand.

Another object of the invention is to provide a double fountain pen designed to contain two 15 differently colored inks or to carry two separate reservoirs of ink of the same color, each of which ink supplies or reservoirs has a pen connected therewith, in which either pen may be submerged in a quantity of ink for filling the 20 reservoir connected therewith without introducing the other pen into the ink.

The invention broadly contemplates the provision of a fountain pen having a longitudinally divided barrel, each of the two divisions constituting an ink reservoir leading to a pen nib. At the end of the barrel opposite the nibs, the barrel sections are swivelly joined together so that they may be swung in planes paralleling the 30 plane of the opposing faces so that either pen may be dipped into an ink reservoir, for filling. Readily removable means at the end of the barrel opposite the swivel connections between the sections maintains the barrel sections normally in operative relation.

35 The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from 40 the salient features of the invention as expressed in the appended claim.

In the drawing:—

Figure 1 is a detail side elevation partly broken away and in section of a device constructed according to the embodiment of this invention.

Figure 2 is a fragmentary longitudinal section partly in detail of the device.

Figure 3 is a fragmentary side elevation showing the manner in which the pen sections are 55 swingably secured together.

Figure 4 is a sectional view taken on the line 4—4 of Figure 1.

Referring to the drawing wherein like numerals of reference designate corresponding parts throughout the several views, the numeral 1 designates the barrel of the pen embodying the present invention. This barrel, as illustrated, is divided longitudinally throughout to form the two semi-cylindrical sections 2, each of the opposing sides of which is closed by a flat wall 3, 10 thus forming two ink or ink sac chambers, each of which is indicated by the numeral 4. In the present case, each of the chambers 4 is illustrated as having an ink sac 5 therein, although it will be obvious to those skilled in the art that 15 the ink may be placed directly in the chamber as in the old fashioned type of fountain pen. Each of these sacs may be compressed in the usual manner by means of a key device 6 when it is desired to exhaust the sac of air for re- 20 filling with ink. This construction is well known in fountain pen art and as it forms no part of the present invention, need not be further described.

The upper end of each of the barrel sections 2 is rounded and thickened, as indicated at 7, and the confronting faces of these thickened portions are connected by a pivot pin 8, thus swivelly joining the sections at this end so that they may have their opposite ends separated in the manner illustrated in Figure 3. In the opposite end of each section 2 from the pivot 8 is fitted a semi-circular plug 9. Each of these plugs is of slightly greater diameter through a portion of its length extending from one end, than the remaining portion so as to form a shoulder 10 which rests upon the end edge of the adjacent flat wall 3 of the barrel section, thus causing the flat sides of the exposed portions of the plugs to be arranged in the same planes as the outer surfaces of the adjacent walls 3. Thus, when the sections 2 are brought together to form the complete barrel, the flat faces of the plugs 9 will be in abutting relation, as illustrated in Figures 1 and 2. The inner end of each plug has an ink sac 5 attached thereto, to feed ink through a suitable passage in the plug to a pen nib 11 which is mounted in the outer end of the plug in the usual manner.

The barrel sections 2 are retained in operative relation by the application of a securing ring 12 which surrounds the barrel adjacent the pen end in the manner illustrated. This ring is preferably internally threaded for engagement with screw threads 13 formed about the barrel. While 55

this construction is preferred, it will be obvious that it is not required that the ring be threaded upon the barrel as a frictional engagement of the same around the barrel may suffice.

- 5   The cap for the pen is indicated by the numeral 14 and this is also interiorly threaded for engagement with the threads 13 when the pen is out of use or for engagement with the threads 15 formed about the barrel adjacent the opposite or 10 upper end where the cap is placed while the pen is being used.

- 15   From the foregoing, it will be readily apparent that the pen may be employed to carry inks of two different colors and when so employed, either 20 color may be readily brought into use by merely rotating the pen one-half a turn between the fingers. It is also contemplated to use the pen, if desired, for one color ink, in which case there will also be an additional supply when one barrel section runs dry and the running dry of this section will be an indicator of the quantity of ink remaining in the pen so that if the section is immediately or shortly thereafter refilled, the user will never be completely out of ink.
- 25   In addition to the foregoing advantages, it will be apparent that another advantage in the present invention resides in the fact that by making a single barrel in two semi-cylindrical reservoirs and placing the pens back to back in the ends 30 of the reservoirs and pivotally connecting the reservoirs at the other ends, either pen may be used without interference by the other and

either barrel may be readily refilled without getting the pen of the other barrel into the ink. After being refilled, the barrel sections are brought together and secured by the ring 12. By this means, the usual pen shape is maintained 5 and no difficulty is experienced in holding the pen in the fingers.

What is claimed is:—

A fountain pen, comprising a pair of elongated receptacles each of semi-cylindrical cross section, 10 said receptacles being normally disposed with their flat faces together to form a complete cylindrical body, the receptacles at one end of the body being closed, a pin member connecting the opposed faces of the receptacles at the closed ends 15 thereof, a pen carrying plug body removably disposed in the other end of each receptacle, the pens of said plug bodies being normally disposed in back to back relation, screw threads extending circumferentially of each receptacle adjacent 20 each end, the threads of the two receptacles being normally matched to extend entirely around the body, an interiorly threaded annulus adapted to encircle the body at the ends adjacent the pens, and an interiorly threaded cap designed to 25 receive either end of the body and to be connected therewith through engagement with the threads thereon said annulus forming a stop for the cap when the latter is in position to cover the pens.

JOSEPH L. HOYLE.
